UNITED STATES PATENT OFFICE.

CHARLES EDMOND EVANS, OF WEED, CALIFORNIA.

KILN-CAR.

1,165,163.

Specification of Letters Patent. Patented Dec. 21, 1915.

Application filed December 13, 1913. Serial No. 806,457.

To all whom it may concern:

Be it known that I, CHARLES E. EVANS, a citizen of the United States, and a resident of Weed, in the county of Siskiyou and

5 State of California, have invented a new and Improved Kiln-Car, of which the following is a full, clear, and exact description.

10 My invention has for its object to provide a kiln car having a main frame and an auxiliary frame movable relatively thereto, on which the lumber or other material is disposed, a bed and a stake of the auxiliary frame being connected by links with a bed 15 and a stake on the main frame so that when the auxiliary frame moves down under the weight of lumber or other material and relatively to the main frame, the links will move the auxiliary frame to press the lumber 20 or other material between the stake on the auxiliary frame and another stake on the main frame. As the whole weight of the lumber or other material is carried on the bed of the auxiliary frame the stake on the 25 auxiliary frame is moved with much force in the direction of the second mentioned stake on the main frame.

Another object of the invention is to 30 provide shoes which are pivoted to the stake on the main frame, these shoes engaging a stake which is raised by the downward movement of the lumber on the car to move the links for pushing the last mentioned stake in the direction of a companion stake 35 on the main frame.

Additional objects of the invention will appear in the following specification in which the preferred form of the invention is disclosed.

40 In the drawings similar reference characters refer to similar parts in all the views in which—

Figure 1 is a side elevation of the kiln car with the auxiliary frame raised; Fig. 45 2 is a side elevation similar to that shown in Fig. 1, but with lumber disposed on the bed of the auxiliary frame to move the auxiliary frame to its lowermost position; Fig. 3 is an end view showing two kiln cars 50 that rotate with lumber; Fig. 4 is a sectional view on the line 4—4 of Fig. 1; Fig. 5 is a plan view showing a tie member for holding the upper portions of the stakes in position; Fig. 6 is a sectional view on the line 55 6—6 of Fig. 1; Fig. 7 is a fragmentary view showing a modified form of link connection

between the stakes and the bed members; Fig. 8 is a sectional view on the line 8—8 of Fig. 7; and Figs. 9 and 10 are views showing modified forms.

60 By referring to the drawings, it will be seen that the main frame 10 has a bed consisting of two parallel members 11 between one set of ends 13 of which there is disposed a base 14 of a stake 12, the base 15 of a stake 16 being disposed between the ends 17 of the members 11 of the bed of the main frame 10. Bolts 18 are provided for securing the base portions 14 and 15 to the ends 13 and 17 of the bed members 11 of the main frame 10. Disposed above the horizontal plane of the bed members 11 there is a bed member 19 of an auxiliary frame 20, this bed member 19 being disposed substantially parallel with the bed members 11. Extending 70 upwardly at one end of the bed member 19 there is a stake 21 which is disposed adjacent the stake 12, the stakes 12 and 21 being connected together by the links 22, these links 22 being normally disposed upwardly 75 from the stake 12 and in the general direction of the stake 16. Links 23 are pivoted at the sides of the bed members 11, these links 23 being disposed upwardly and in the general direction of the stake 16, the upper ends 80 of the links 23 being pivoted to the bed member 19. It will, therefore, be seen that when the bed member 19 is held in the raised position shown in Fig. 1 of the drawings and lumber or other material is piled on the 85 bed member 19 and between the stakes 16 and 21, that the weight of the lumber will tend to force the member 19 down relatively to the bed members 11, and that such movement of the bed member 19 will cause the 90 auxiliary frame 20 to move in the direction of the bottom of the stake 16, thereby pressing the lumber or other material between the stakes 16 and 21. Guide members 24 are secured to the end of the bed member 95 19, these guide members 24 being disposed at the outer sides of the stake 16 for guiding the bed member 19 of the auxiliary frame 20 in its movement in the direction of the base of the stake 16. As a means of holding the upper portions of the stakes 16, 12 and 21 in position, I provide a tie member 25 having a loop 26 disposed around the stake 16, the tie member 25 having another loop 27 disposed around the stake 12 and 100 the stake 21. The main frame 10 is supported by wheels or rollers which are dis-

posed between the bed members 11 and which are mounted on axles 29 secured to the said bed members 11.

In the modified form of the invention shown in Fig. 9 of the drawings, the bed member 30 is supported at one end by the wheel or roller 31, a lever 32 being pivoted at 33 to the bed member 30, this lever 32 extending in the direction of the other end 10 of the bed member. To the lever there is journaled the other supporting wheel 34. At the end 37 of the bed member 30 there is secured a vertically disposed stake 36. At the end 37 of the bed member 30 there is 15 secured a vertically disposed stake 38, links 39 being pivoted to the stake 38, these links 39 having pivoted to them shoes 40 which engages a member or stake 41 resting on the lever 32. It will, therefore, be seen that 20 when the lumber is disposed on the bed member 30, that the weight of the lumber will force the bed member 30 down relatively to the lever 32, thereby lowering the stake 38 relatively to the stake 41 and moving the links 39 to horizontal positions. This movement of the links 39 will force the member or stake 41 in the general direction of the stake 36 to clamp the lumber or other material therebetween.

30 I prefer to pivot the stake 21 to the bed member 19 for greater flexibility.

The links 42 in Figs. 7 and 8 have cam extensions 43 at their ends for engagement with the flanges 44 on the stakes 12^a and 21^a 35 so that when the stake 21^a descends with the bed member 19 the cam extensions 43 will engage the flanges 44 to move the stakes 21^a away from the stake 12^a, the link pivot pins 45 moving in the slots 46 in the stakes 12^a and 21^a. These cam extensions 43 are 40 set off for engagement with the flanges 44 and as soon as the links are moved toward horizontal positions, the engagement of the cam extensions 43 with the flanges 44 will 45 serve to push the stake 21^a away from the stake 12^a.

The stake 21 may be connected with the bed 19 by a pin 19^a, which is disposed through an orifice in the stake 21 and which 50 extends through a slot 19^b in the bed 19.

Another means of connecting the stake 21 and the bed 19 is shown in Fig. 10 of the drawings, this means consisting of a link 19^c 55 which is pivoted at one end to the stake 21 and at the other end to the bed 19.

It is understood that while the car is being loaded the auxiliary frame 20 may be supported by a block or by any other suitable means.

60 Having thus described my invention, I claim as new and desire to secure by Letters Patent:

1. In a kiln car, a main frame having a bed member and two stakes spaced apart, an auxiliary frame having a bed member and a

stake, and links connecting the two bed members and one of the stakes on the main frame with the stake on the auxiliary frame.

2. In a kiln car, a main frame having a bed member, two stakes spaced apart, an auxiliary frame having a bed member and a stake, links connecting the two bed members and one of the stakes on the main frame with the stake on the auxiliary frame, and a guide on the bed member of the auxiliary frame for engaging one of the stakes on the main frame.

3. In a kiln car, a main frame having a bed member, a stake at one end of the bed member, an auxiliary frame having a bed member, and a stake spaced from the first mentioned stake, and links pivoted to the bed member of the auxiliary frame, the links extending in the general direction of the other end of the bed member of the main frame and pivoted to the last mentioned bed member.

4. In a kiln car, a main frame having a bed member, a stake at one end of the bed member, an auxiliary frame having a bed member and a stake spaced from the first mentioned stake, links pivoted to the bed member of the auxiliary frame, the links extending in the general direction of the other end of the bed member of the main frame and pivoted to the last mentioned bed member and a guide on the bed member of the auxiliary frame for engaging the stake on the main frame.

5. In a kiln car, a main frame having a bed member, a stake at one end of the bed member, an auxiliary frame having a bed member and a stake spaced from the first mentioned stake, links pivoted to the bed member of the auxiliary frame, the links extending in the general direction of the other end of the bed member of the main frame and pivoted to the last mentioned bed member and means for guiding the auxiliary frame relatively to the main frame.

6. In a kiln car, a main frame having two stakes spaced apart, an auxiliary frame having a stake disposed adjacent one of the stakes of the main frame and a link pivoted to the last mentioned stake of the main frame, the link extending upwardly and being pivoted to the stake of the auxiliary frame.

7. In a kiln car, a main frame having two stakes spaced apart, an auxiliary frame having a stake disposed adjacent one of the stakes of the main frame, a link pivoted to the last mentioned stake of the main frame, the link extending upwardly and being pivoted to the stake of the auxiliary frame, and means for guiding the auxiliary frame relatively to the main frame.

8. In a kiln car, a main frame having a stake, an auxiliary frame having a stake, disposed above and adapted to move down

5 relatively to the main frame, and means connecting the two frames for moving the auxiliary frame in the direction of the stake on the main frame as the auxiliary frame moves downwardly.

10 9. In a kiln car, a main frame having a bed member and two stakes spaced apart, an auxiliary frame having a bed member and a stake pivoted thereto and links connecting the two bed members and one of the stakes 15 on the main frame with the stake on the auxiliary frame.

15 10. In a kiln car, a main frame having a bed member and stakes spaced apart, an auxiliary frame having a bed member and a stake, links having cam ends, pin and slot connections between the links and the frames, and flanges on the frames for engagement by the cam ends.

20 11. In a kiln car, a main frame having a bed member and stakes spaced apart, an auxiliary frame having a bed member and a stake, links having cam ends, pin and slot connections between the links and a stake 25 on each of the frames, flanges on the last mentioned stakes for engagement by the cam ends and additional links connecting the two frames.

25 12. In a kiln car, a main frame having two stakes spaced apart, a stake for moving vertically under a weight, means for

30 moving the stake, links having cam ends, pin and slot connections between the links, the last mentioned stake, and one of the first mentioned stakes and flanges on the stakes 35 for engagement by the cam ends.

35 13. In a kiln car, a main frame having two stakes, there being slots and a flange on one of the stakes, a stake for moving relatively to the first mentioned stakes, there being slots and a flange on the third mentioned stake, means operable by a weight for moving the third mentioned stake, links having 40 cams for engaging the flanges and pins for the links for moving in the slots.

40 14. In a kiln car, a main frame having a bed member and two stakes spaced apart, an auxiliary frame having a bed member and a stake, links connecting the two bed members, links connecting one of the stakes 50 on the main frame with the stake of the auxiliary frame, and a link connecting the stake of the auxiliary frame with the bed member of the auxiliary frame.

50 In witness whereof I have signed my name to this specification in the presence of the two subscribing witnesses.

CHARLES EDMOND EVANS.
